His Attorney.

UNITED STATES PATENT OFFICE

FREDERICK DAVID AUSTIN, OF PORT CHESTER, NEW YORK, ASSIGNOR OF ONE-HALF TO
DAVID J. KELLY, JR., OF PORT CHESTER, NEW YORK

TEAKETTLE AND LIKE DOMESTIC BOILER

Application filed May 21, 1929. Serial No. 364,843.

This invention relates to improvements in portable domestic water heaters, and more particularly to the type commonly designated tea-kettles.

5 The primary object in view is maximum efficiency in heat transference, and a further object is the raising of the temperature of a relatively small quantity of water quickly to a high degree with a minimum expenditure 10 of fuel.

With these and further objects in view as will in part hereinafter become apparent and in part be stated, the invention comprises certain novel constructions, combinations, 15 and arrangements of parts as subsequently specified and claimed.

In the accompanying drawings,—

Figure 1 is a sectional elevation of a tea-kettle involving the features of the present 20 invention.

Figure 2 is an inverted plan view thereof.

Figure 3 is a diagrammatic illustration on a reduced scale of the same structure attached to deliver steam to a domestic cooker.

25 Referring to the drawings by numerals, 1 indicates the body having the conventional exterior contour of an ordinary tea-kettle and provided with the usual spout 2 and removable cover 3. An appropriate bail or other handle 4 is customarily connected as a 30 convenient means of manually transporting or otherwise handling the body 1 and its connected parts. The body 1 is also provided with the usual bottom 5, but the bottom 5 35 differs from the conventional tea-kettle bottom by being formed up into a dome 6 within the body 1. Dome 6 leaves a water leg or space 7 between itself and the surrounding wall of the body 1. Dome 6 may be of any 40 desired cross sectional area and of any of various peripheral contours, but it is desirable that the water leg or space 7 shall be comparatively thin with respect to the diameter of the body 1. The dome 6 is made up 45 of an upstanding wall and a top or closure 8, said wall and top being preferably integral with each other and also integral with the bottom 5. The upper surface of the top 8 at its highest point is substantially below the 50 highest point of exit through the spout 2, so

that the water level may be above the cover plate 8 and still provide for the exit of vapor or steam through the spout 2.

Within the dome 6 are arranged water circulating coils 9, each consisting of a pipe 55 communicating at 10 with a lower portion of the water leg 7 and at 11 with an upper portion of the water within the body 1 preferably through the cover plate 8. The pipe of each coil 9 is extended within the dome 6 60 practically the full width across the dome, and then folded back upon itself in a series of flights each slightly upwardly inclined from starting point 10, so that a continuous upward path is provided for water travelling 65 from the point 10 to the point 11. The alternate coils 9 at their lower ends are preferably connected at one side of the dome 6 and the other alternate coils are connected at the 70 opposite side.

The thus constructed tea-kettle or similar portable domestic water heater is adapted for use exactly as any ordinary tea-kettle, but the efficiency is so much greater than the average tea-kettle that the structure is well 75 adapted for use as a vapor or steam generator, for domestic purposes. When the tea-kettle is supplied with water and placed over a source of heat, such as a gas burner, the heat acts on the bottom 5 and on the coils 9 80 and also on the exposed surfaces of the dome 6 and cover plate 8. Fluting or corrugation of plate 8 may be provided for increasing the surface exposed directly to the heat action, but more surface exposure to flames or other 85 sources of heat has not been found by me to alone effect satisfactory results or to distinctively characterize a structure as superior to those previously known. However, the functioning of the coils 9 is such as to produce distinctive and superior results. The heat influencing the water within the lower laps or flights of the coils 9 causes the water to ascend in the coils and discharge at the places 11. The cooler water follows in 90 through the intake ends 10, and, being heated, rises and thus circulation continues.

The resulting action is such that I have been able to boil water in a time unprecedently brief. I have raised water from a tem- 100

perature of 50° to a point above 212° F., when treating but a quart of water, in thirty seconds, and, when treating a gallon of water, I have brought the whole gallon to a boiling point in two minutes, and, under favorable conditions, in a slightly less time. This has been accomplished by me by the use of the structure as illustrated and above described when applied on an ordinary gas burner of the type commonly found in the kitchen gas range.

The several coils 9 have their ends connected to the respective penetrated walls by being spun or otherwise anchored thereto, preferably substantially in the same manner as the connection of the spout of the kettle to the body thereof. Of course, other means of connection, such as brazing or even screw-threading, may be employed when and as desired.

Because of the unusual high degree of efficiency in heat transference manifested by the structure described, I have found the structure especially well adapted for use as a source of vapor or steam for limited uses, such as the supply of steam to a clothes pressing machine or for steam cookers. As a means of demonstrating this utility of the present invention, the body 1 is preferably provided with a return pipe connection 12 capped at 13 when the tea-kettle is to be used in the ordinary fashion and not as a source of steam. The spout 2 is preferably threaded at 14, and when the device is intended to supply steam for any purpose, a riser pipe 15 is connected to the spout 2 by means of the threads 14, while the pipe 12 is connected to a return pipe 16. The pipe 15 may be caused to communicate with a steam or pressure cooker 17, or other instrument, for utilizing steam or vapor, and, of course, the return pipe 16 is connected to receive the drain from such instrument.

What is claimed is:—

1. A portable water heater comprising an enclosing body, a dome within the body opening through the bottom thereof, and a plurality of water circulating coils within the dome, each communicating at one end at a lower point and at the other end at an upper point of the interior of the body, said coils being laterally spaced with respect to each other and each comprising superimposed and aligned flights, all parts of each coil with its connections being entirely free from and spaced laterally of the adjacent coils.

2. A portable water heater comprising an enclosing body, a dome within the body opening through the bottom thereof, and a plurality of water circulating coils within the dome, each communicating at one end at a lower point through the dome and at the other end through the top of the dome, said coils being laterally spaced with respect to

each other and each comprising superimposed flights, the coils extending substantially across the dome and each coil having its ends at the same side of the dome, the ends of adjacent coils being at alternately opposite sides of the dome.

3. A portable water heater comprising an enclosing body, a dome within the body opening through the bottom thereof and terminating short of the top of the body, the dome having a corrugated cover, and a plurality of water circulating coils arranged within the dome and spaced apart laterally, each communicating at one end at a lower point through the dome and at the other end through the corrugated cover of the dome, and each comprising superimposed and aligned flights, and each coil extending substantially across the dome at each flight and having its ends substantially at the same side of the dome.

4. A portable water heater comprising an enclosing body, a dome within the body opening through the bottom thereof, and a plurality of laterally spaced water-circulating coils within the dome, each communicating at one end at a lower point through the dome and at the other end through an upper portion of the dome, both ends of each coil being arranged substantially at the same side of the dome and at the opposite side from the laterally adjacent coils, all parts of each coil with its connections being entirely free from and spaced laterally of the adjacent coils.

In testimony whereof I affix my signature.

FREDERICK DAVID AUSTIN.
